STEEL WOOL HOLDER

William A. Baker, San Rafael, Calif., assignor to
 Baker Novelty Company, Los Angeles County,
 Calif., a corporation of California

Application February 10, 1948, Serial No. 7,396

1 Claim. (Cl. 15—209)

1

This invention relates to scouring devices, and more particularly to holders for steel wool and the like used by housewives for cleaning cooking utensils and other household articles.

A main object of the invention is to provide a novel and improved steel wool holder which is very simple in construction, easy to handle and in which the steel wool may be readily replaced when worn beyond the point of usefulness.

A further object of the invention is to provide an improved steel wool holder which is very inexpensive to manufacture, sturdy in construction and wherein the steel wool is firmly secured so that it cannot readily work loose while it is being rubbed against a utensil surface or other surface to be scoured.

Further objects and advantages of the invention will become apparent from the following description and claims, and from the accompanying drawings, wherein:

Figure 1 is an elevational view of a steel wool holder constructed in accordance with the present invention.

Figure 2 is a vertical cross-sectional view taken through the steel wool holder of Figure 1.

Figure 3 is a top plan view of the steel wool holder of Figure 1.

Figure 4 is a bottom plan view of the holder of Figure 1 with the steel wool removed.

Referring to the drawings, 11 designates a generally cylindrical shell of light gauge sheet metal having a centrally apertured top wall 12 and formed around its periphery with depending bendable spaced fingers 13. Each finger 13 is inwardly struck at 14 to define an inwardly extending barb or spur 15 and the fingers 13 are also curved inwardly at their lower ends as shown at 16, said lower ends being downwardly tapered to define clawlike elements adapted to become readily embedded in a mass of steel wool. Designated at 17 is a cylindrical body, formed of wood or other suitable non-corrosive material, said body having an axially located top projection 18 which extends slidably through the aperture in the top wall 12 of shell 11 and normally projects a substantial distance thereabove. As shown in Figure 2, body 17 is loosely contained within shell 11 and is movable axially with respect thereto. Secured centrally to body 17 is a depending hook element 19. Engaged with hook element 19 is a mass of steel wool 20 said mass being further engaged by the claw fingers 13, the fingers being bent slightly inwardly to cause the spurs 15 to become embedded in the mass 20.

In employment of the device, it is held in the palm of the hand, the fingers gripping shell 11 and the palm exerting pressure on the projection 18, whereby force is transmitted to the steel wool mass 20 during the scouring operation.

In order to clean the device, it is simply held under a stream of hot water, as under an open faucet, the water being allowed to enter the

2

spaces between the fingers 13 as well as the mass of steel wool 20. This dislodges dirt particles from the device, whereby it may be maintained in a sanitary condition.

When the steel wool has become worn and abraded beyond the point of further usefulness, it is removed from the holder and a new mass of steel wool is placed therein. The new wool is crowded into the space defined by fingers 13 by the use of any suitable blunt implement. When said space is filled with steel wool, the projection 18 is rotated about one-half of a turn, causing the hook 19 to engage itself in the new mass of steel wool. As the mass becomes worn by use it is fed downwardly relative to shell 11 by the pressure exerted by the palm of the hand on projection 18.

By the use of the holder above described, the steel wool is used with maximum efficiency and with minimum waste of wool.

While a specific embodiment of a steel wool holder has been disclosed in the foregoing description, it will be understood that various modifications within the spirit of the invention may occur to those skilled in the art. Therefore, it is intended that no limitations be placed on the invention except as defined by the scope of the appended claim.

What is claimed is:

A scouring pad holder, comprising a cylindrical shell having a top provided with a central opening and being open at its bottom end, circumferentially spaced depending resilient prongs secured to the lower end of the shell and extending below the shell for a substantial distance, the prongs being provided near their lower free ends with radially inwardly projecting integral barbs, a cylindrical block loosely mounted within the cylindrical shell above the prongs and freely shiftable axially therein, the upward axial movement of the block being limited by the top of the shell, the block including a central upstanding knob slidably projecting through the opening of the top of the shell, and a centrally located hook secured to the bottom of the block, the prongs receiving within them and surrounding a scouring pad, the hook and barbs engaging within the scouring pad, the block serving as a plunger to feed the scouring pad downwardly when the knob is depressed.
